UNITED STATES PATENT OFFICE.

THEODORE J. PAGEL, OF MINNEAPOLIS, MINNESOTA, ASSIGNOR TO PAGEL ROTARY PUMP MANUFACTURING COMPANY, OF MINNEAPOLIS, MINNESOTA, A CORPORATION OF MINNESOTA.

ROTARY PUMP.

1,085,290.

Specification of Letters Patent. Patented Jan. 27, 1914.

Application filed November 11, 1912. Serial No. 730,689.

To all whom it may concern:

Be it known that I, THEODORE J. PAGEL, a citizen of the United States, residing at Minneapolis, in the county of Hennepin and 5 State of Minnesota, have invented certain new and useful Improvements in Rotary Pumps; and I do hereby declare the following to be a full, clear, and exact description of the invention, such as will enable others skilled in the art to which it 10 appertains to make and use the same.

My invention relates to rotary pumps, and has for its object to improve the construction and increase the efficiency of 15 pumps of this type.

Particularly, the invention has for its object to provide an improved multiplex rotary pump, and means whereby, when a large volume of water is desired, several 20 pumps may be simultaneously operated from a common source of energy, and when relatively high pressure, but less volume of water is desired, any one, or less than the whole number of pumps may be thrown out 25 of action and the entire driving force utilized to drive the same.

Generally stated, the invention consists of the novel devices and combinations of devices hereinafter described and defined in 20 the claims.

In the accompanying drawings which illustrate the invention, like characters indicate like parts throughout the several views.

25 Referring to the drawings, Figure 1 is a plan view of the improved pump with some parts broken away; Fig. 2 is a front elevation thereof; Fig. 3 is a side elevation of the pump, some parts being broken away; 40 Fig. 4 is a vertical section taken on the line $x^4 x^4$ on Fig. 2; Fig. 5 is a horizontal section taken on the line $x^5 x^5$ on Fig. 2; and Fig. 6 is a vertical section taken on the line $x^6 x^6$ on Fig. 5.

45 The main casing of the pump is preferably made up of an intermediate section 1 and end sections 2, which parts are bolted together, or otherwise connected with water tight joints. Near the ends of the section 1, 50 this casing is formed with intersecting cylindrical piston chambers or seats 4, and, at its central portion, the said section 1 is formed with a tubular gear housing 5 that extends through the same from front to 55 rear, but has no communication with the in-

terior of said casing. Just below the housing 5, the case section 1 is formed with a cylindrical valve seat 6 that opens into the two compartments a and b of the main casing through ports 6^a and 6^b (see Fig. 6). 60 Working in the valve seat 6 is a segmental rotary valve 7, which, at one end has a head 8 that closes the end of the valve seat 6 and is connected to an operating crank 9 (see Fig. 4). The other end of the valve seat 6 is connected to a water supply pipe 10 and this same end of the valve 7 is open, so that the water flows directly into the said valve seat, and from thence, through one or the other or through both of the ports 6^a and 6^b 65 into one or the other or both of the main compartments a and b of the casing. Horizontal partitions 11 (see Fig. 6) divide the compartments a and b of the casing into upper and lower sections. Below the partitions 11, the sides of each piston seat 4 are provided with inlet ports 4^a and above said partitions 11, both sides of each piston seat 4 are provided with outlet ports 4^b . The upper sections of the compartments a and b , 70 on opposite sides of a central upper partition 12, are provided with discharge ports 13 a and 13 b that are normally closed by lightly spring-pressed upwardly opening 75 check valves 14, located in a discharge chamber 15 bolted or otherwise rigidly secured with a water tight joint to the top of the main casing. This discharge chamber 15 is shown as provided with discharge 80 passages 16 a , and with a threaded neck 16 to which latter an air chamber, not shown, is adapted to be connected. In each horizontal partition 11 is a by-pass port 17 that is normally closed by a so-called by-pass 85 valve 18, shown as provided with a threaded stem 19 working in the top of the corresponding case section 2.

Working in the intersecting cylindrical piston seats 4 are rotary gear-like pistons 20, each of which, as shown, has two diametrically opposite teeth or propelling lugs 21 and two diametrically opposite lug seats 22. Of course, the number of these propelling lugs and seats may be varied. The propelling lugs 21 work with close engagement 100 with the sides and peripheral walls of the respective seats 4, and are adapted to engage in the proper order with the so-called lug seats 22 of coöperating rotary pistons. The base portions of the propelling lugs 21 105 110

are preferably struck off a curve of greater arc than are the outer portions of the said lugs. This gives the wearing contact at the base of said lugs and gives clearance between the more inwardly extended curved surfaces and the walls of the lug seats 22. The bottoms of the said lug seats 22 (see Figs. 4 and 5) are formed with laterally spaced approximately straight ribs 20^a and 10 with intervening channels 20^b. The ends of the propelling lugs 21 and the outer extremities of the packing blades 25 engage with the said ribs 20^a and the channels 20^b afford ample opportunity for water to escape from one side to the other of the packing strips and the outer extremities of the said lugs, thereby preventing the water which is caged in the lug seats 22 from locking or blocking the movement of the 20 rotary pistons.

The solid portions of the bearings 27 (see Figs. 3 and 5) immediately adjacent to the rotary pistons 20 are formed with annular grooves 27^a that are connected by small return ducts 27^b to the suction sides; that is, to the lower sections of the compartments *a* and *b* of the casing, so that any water which leaks into the said grooves 27^a will be thrown back into the casing. This very greatly reduces the pressure of the water at the journals and correspondingly reduces the tendency toward leakage. Preferably, the said pistons 20 are formed adjacent to the bases of their lug seats 21 with depression 23, to 35 receive projecting ribs 24 formed on the co-operating partitions adjacent to the lug seats 22. This extends the operative surface of the propelling lugs inward of their pitch lines and forms a better joint for preventing 40 leakage of water between the engaging propelling lugs and seats. The propelling lugs are preferably formed on the line of involute curves, but may be formed on any other desirable curves which will give a good 45 gear action. The propelling lugs may be and preferably are provided with packing strips 25 which form close engagement with the cylindrical walls of the piston seats.

Each co-operating rotary piston 20, on one 50 side, is axially aligned with a corresponding piston on the other side of the casing; and these axially aligned pistons are rigidly secured to common shafts 26 journaled in suitable bearings 27 and extended through suitable stuffing boxes 28 on the main casing. The bearings 27 are preferably roller bearings (see particularly Fig. 5) in which view some of the roller bearings are removed and others are shown in position. The shafts 26 55 are, of course, parallel to each other and both extend transversely through the gear housing 5, and within the said gear housing, they are provided with rigidly secured intermeshing pinions 28, which cause the 60 several rotary pistons to move in synchro-

nism. These gears 28 take the main driving friction and relieve the co-operating rotary pistons from wearing friction. One of the shafts 26 is extended at one end and provided with a driving element shown in the 70 form of a pulley 29, over which a power driven belt, not shown, is adapted to be run to impart rotary movements to the co-operating pistons. Preferably, the case sections (see particularly Figs. 1 and 5), are provided with outer shaft bearing lugs 30 in which also ball bearing devices, not shown, are adapted to be applied, to afford good supports for the outer ends of the shafts 26. 75

The operation of this improved pump is substantially as follows: When the by-pass ports 17 are closed by the by-pass valves 18, the only communication between the upper and lower portions of the compartment *a*; or of the compartment *b*, is through the piston seats 4, and to carry water through these piston seats 4, rotary movements of the pistons are required. As is evident, when the admission valve 7 is in the position shown in Fig. 6, and the pistons are then rotated in 90 the direction of the arrow marked on Fig. 4, both of the rotary pumps will simultaneously act to pump water in a direction from the supply pipe 10, out through the neck 16 of the discharge chamber 15. The valves 14 95 are so lightly seated that they offer very little resistance to the flow of the water, but nevertheless, they check a reverse flow when the pumps are idle. When the valve 7 is turned toward the left, so as to close the port 100 6^a, only the right hand pump will be in action, and on the other hand, when the said valve is turned toward the right, so as to close the port 6^b, only the left hand pump will be thrown into action. When one of 105 the rotary pumps is thrown out of action, the by-pass valve 18 on that side of the pump casing, to-wit, on the closed side of the pump casing, should be opened up so that water caged in that closed side of the casing 110 will be free to circulate through the co-operating by-pass port 17. This prevents excessive resistance due to rotation of the idle or in-operative pump. Obviously, when only one pump is in action, only one-half as 115 much water will be pumped as when both pumps are in action, but all of the driving force is then available on one pump, so that water can then be delivered under approximately twice as much pressure and approximately twice as great an altitude as when both pumps are in action.

The pump illustrated is a duplex or twin rotary pump, but it will, of course, be understood that the pump may be made in more 120 than two sections, and, furthermore, that many of the features of this invention are capable of use in a single or simple rotary pump of the character described. It is easily seen that this feature of the pump, in 125 130

addition to the provision made for the free escape of the fluid trapped between the intermeshing teeth, will greatly increase the capacity and efficiency of this pump over the ordinary rotary pump, where the water is forced to enter from below in a direction directly opposing the rotating propellers. With this old construction the momentum of the inrushing water striking against the propellers moving in the opposite direction, exerts a strong reacting force against the rotation of the pistons. The piston or propeller teeth are called upon to suddenly arrest the rush of water against them, divert the stream first backward and then in two opposite directions at right angles to the original flow. This action entails a considerable loss of power, in the ordinary rotary pump, especially when pumping from hydrants under pressure as a fire engine pump. It also increases the slippage and decreases the capacity of the pump, as the tooth spaces are apt to be incompletely filled with water. On the outlet side of the ordinary pump there are no means, whereby the water, that is forced out of the tooth space when the tooth enters, can escape sidewise, to the outlet port, but it must be forced backward out between the entering tooth and the cavity walls, and when the tooth closes in the space or cavity, the remaining water can not escape in that direction at all, but is propelled with great force against the side walls of the pump, consuming power and sometimes even resulting in breakage. This defect is entirely obviated in the applicant's improved pump, as the outlet ports are in the side walls of the pump casing, and these ports are both in free communication with the tooth cavities of the pistons up to the point where the greatest displacement has taken place. The water remaining in the clearance space is released from pressure and the water displaced by the inmeshing tooth is discharged freely in both sidewise directions from the tooth space into the lateral outlet ports, under normal pressure. It will be seen therefore, that this peculiar construction and location of both the intake and discharge ports adds greatly to the efficiency, capacity and smooth running of the pump. The ports are located at opposite sides of a line drawn through the centers of the pistons, and the distance between them across this center line, is substantially the width of a tooth or a tooth cavity, with a slight lap. In this pump, two or more distinct pumping units are provided, and the whole force of the primary power may be concentrated on one or more of the units by operation of the admission valve 7. When the admission is shut off from one unit the added pressure resulting from a continued operation of the remaining pump or pumps, acts to close the check valve 14 of the inoperative pump and

prevents the return of water into that particular pump compartment. The opening of the relief valve 18, permits the water remaining in the intake and outlet compartments of the inoperative pump to circulate freely within the compartment. The valves 18 are not emergency or check valves to prevent injury or rupture, because the check valves 14 will prevent this, but the said valves 18 act simply to prevent unnecessary back pressure on the idle running pump.

This improved pump is of simple construction, of comparatively small cost, has few parts to get out of order and is highly efficient for the purposes had in view.

What I claim is:

1. The combination with a casing provided with intersecting cylindrical piston chambers, of coöperating rotary pistons working within the said chambers, the said pistons having peripheral tooth members and coöperating tooth cavities arranged alternately and extending across the periphery of the said pistons to the side walls of the said piston chambers, means arranged in both sides of the said pistons and in both sides of the said chambers for admitting water in a lateral direction into the said tooth cavities, and an exhaust port leading from the said cylindrical piston chambers.

2. The combination with a casing provided with intersecting cylindrical piston chambers, of coöperating rotary pistons working within the said chambers, the said pistons having peripheral tooth members and coöperating tooth cavities arranged alternately and extending across the periphery of the said pistons, means arranged in both sides of the said pistons and in both sides of the said chambers for admitting water in a lateral direction into the said tooth cavities and for discharging the water, in a lateral direction, from the said tooth cavities and from the said piston chambers.

3. The combination with a casing having intersecting cylindrical piston chambers, of rotary pistons working in said chambers and having intermeshing peripheral teeth, said casing having admission ports opening into said intersecting piston chambers through both sides of the intersecting portions of the sides thereof, and at points past which the teeth of said pistons sweep under rotation of the pistons, and an exhaust port leading from the said piston chamber.

4. The combination with a casing having intersecting cylindrical piston chambers, of rotary pistons working in said chambers and having intermeshing peripheral teeth, said casing having in both sides thereof admission and exhaust ports located at the intersections of said piston chambers and at points past which the teeth of said pistons sweep under rotation of said pistons.

5. The combination with a casing having

a compartment divided into upper and lower sections, and provided with intersecting cylindrical piston chambers, of rotary pistons working in said chambers and having intermeshing peripheral teeth, said casing having admission and exhaust ports that open into said piston chambers through the side thereof, at the intersections of said piston chambers and at points past which the teeth of said pistons sweep under rotation of said pistons.

6. The combination in a system of multiple pumping units, having separate intersecting cylindrical piston chambers and intermeshing rotary pistons working within the said chambers, of admission and exhaust ports leading, respectively, to and from the said piston chambers, a water supply conduit having branch connections to the admission ports of the several pumping units, a throttle valve at the junction of said supply conduit and its branches, movable into one position to admit water to the several admission ports and movable into another position to shut the water off from one of the said admission ports while admitting water to another admission port, and a check valve arranged in one of the exhaust ports to automatically prevent the water from entering the piston chambers of the pumping unit, the admission port of which has been shut off.

7. The combination in a system of multiple pumping units, having separate intersecting cylindrical piston chambers and intermeshing rotary pistons, working within the said chambers, of admission and exhaust ports leading, respectively, to and from the said piston chambers, a water supply conduit having branch connections to the admission ports of the several pumping units, a throttle valve at the junction of said supply conduit and its branches, movable into one position to admit water to the several admission ports and movable into another position to shut the water off from one of the said admission ports while admitting water to another admission port, a check valve arranged in one of the exhaust ports to automatically prevent the water from entering the piston chambers of the pumping unit, the admission port of which has been shut off, and normally closed valve equipped by passage connecting the admission and exhaust ports of the respective pump units.

5. 8. The combination with a casing having a compartment divided into upper and lower sections, and provided with intersecting cylindrical piston chambers, of rotary pistons

working in said chambers and having intermeshing peripheral teeth, said casing having admission and exhaust ports that open into said piston chambers through the side thereof, at the intersections of said piston chambers and at points past which the teeth of said pistons sweep under rotation of said pistons, said casing having between said admission and exhaust ports a bridge that is wider than the tangential width of the tooth cavity of said pistons, whereby lap is afforded to prevent leakage.

9. The combination with a casing having intersecting cylindrical piston seats and inlet and outlet ports, of coöperating rotary pistons working in said seats and having intermeshing propelling lugs and lug seats, the said pistons at the base of said propelling lugs having notches extending the bearing surfaces thereof inward of the pitch line, and having for engagement therewith, ribs adjacent to the lug seats extending the bearing surfaces outward of the pitch line.

10. The combination with a casing having intersecting cylindrical piston seats and inlet and outlet ports, of coöperating rotary pistons working in said seats and having intermeshing propelling lugs and lug seats, said lug seats having laterally spaced ribs at their bottoms and escape passages between said ribs, substantially as described.

11. The combination with a casing having intersecting cylindrical piston seats and inlet and outlet ports, of coöperating rotary pistons working in said seats and having intermeshing propelling lugs and lug seats, the said lug seats having laterally spaced ribs at their bottoms and escape passages between the same, and the said propelling lugs having packing blades engageable with the said laterally spaced ribs of said lug seats, substantially as described.

12. In a rotary pump, the combination with a casing having intersecting cylindrical piston seats and intermeshing rotary pistons working therein, said pistons having shafts, and said case having bearings for said shafts, said bearings having annular grooves surrounding said shafts adjacent to said rotary pistons and return ducts leading to the suction sides of the interior of said casing, substantially as described.

In testimony whereof I affix my signature in presence of two witnesses.
